UNITED STATES PATENT OFFICE.

JOSEPH SILVERMAN, OF CHICAGO, ILLINOIS.

DESIGN FOR A WIRE CHAIR-BACK.

49,401.

Specification for Design.

Patented July 18, 1916.

Application filed December 30, 1915. Serial No. 69,495. Term of patent 7 years.

To all whom it may concern:

Be it known that I, JOSEPH SILVERMAN, a citizen of the United States, residing at Chicago, in the county of Cook and State of Illinois, have invented a new, original, and ornamental Design for Wire Chair-Backs, of which the following is a specification, reference being had to the accompanying drawing, forming part thereof.

The figure is a perspective view of a wire chair back showing my new design and indicating in dotted line the relation of the chair thereto, which latter however forms no part of the present invention.

I claim:—

The ornamental design for a wire chair back as shown.

JOSEPH SILVERMAN.
